G. DEAKIN,
AUTOMATIC TELEPHONE EXCHANGE SYSTEM,
APPLICATION FILED MAR. 27, 1912.

Patented June 6, 1916.

UNITED STATES PATENT OFFICE.

GERALD DEAKIN, OF SAN FRANCISCO, CALIFORNIA, ASSIGNEE, BY MESNE ASSIGNMENTS, TO WESTERN ELECTRIC COMPANY INCORPORATED, A CORPORATION OF NEW YORK.

AUTOMATIC TELEPHONE-EXCHANGE SYSTEM.

1,185,635.

Specification of Letters Patent.

Patented June 6, 1916.

Application filed March 27, 1912. Serial No. 686,570.

To all whom it may concern:

Be it known that I, GERALD DEAKIN, a citizen of the United States of America, and a resident of San Francisco, San Francisco county, California, have invented a new and useful Improvement in Automatic Telephone-Exchange Systems, of which the following is a specification.

My invention pertains to an improved party line ringing circuit, applicable to telephone systems in general, with particular reference to automatic telephone systems.

In the automatic telephone systems now in successful commercial operation, it is the common practice to terminate the line from the subscriber's station at the central office, either directly or indirectly, on a "selector switch" or other similar piece of switching apparatus. The function of the "selector" is to automatically extend the connection from the calling station in response to impulses originating at said calling station, to the proper switch which makes the final connection with the called line. This latter switch is commonly known as a "connector switch" or simply a "connector." The form of "connector" now in general use is arranged to select the last two digits of a number, all preceding digits being selected by "selectors."

Thus, in an automatic telephone exchange of a capacity requiring the use of four digits in all numbers, the first two digits in every case would be selected by first and second "selectors" respectively, and the last two digits by a "connector."

Where party line service in an automatic telephone exchange is desired, it is now customary to provide a plurality of classes of connectors, there being as many classes of connectors as there are stations on a party line. Each class of connector is arranged to call its corresponding class of station only, and each party line, by the proper multiplying of its contacts in the connector "banks" is made available to as many classes of connectors as there are classes of stations. Therefore, by assigning such numbers to the various stations on a party line as will cause the proper connector to be picked up automatically during calling, no special operating methods are required on the part of the calling subscriber in establishing a connection with any one of the stations on a party line.

As previously stated, the connector selects

the last two digits of a number and selectors all preceding digits. Therefore, it may be said that the purpose of the selectors is to select automatically, the proper connector. The selectors now in common use are arranged to select an idle trunk in any one of ten groups of trunks, running to other selectors or to connectors. The first group corresponds to the figure 1, and is selected by calling one (1) on the subscriber's station dial; the second group to the figure 2, and so on to the tenth group which corresponds to the figure 0. Since the connector must select the last two digits of every number it follows that each connector must have access to at least one hundred lines, i. e., 00, 01 to 98, 99. To illustrate the present practice more fully, consider for example, a party line system in which there are four stations on a line. In this case, there would be four classes of connectors, each class having access to the same group of lines. This would be accomplished by multiplying the connector bank contacts, the 100 sets of contacts being numbered from 00, 01 to 98, 99, before each class of connector. To permit the selection of the proper connector, it is only necessary to connect each class of connector to different groups of bank contacts or levels on the preceding selectors. Thus, in the particular case of the four party line cited, the first class of connectors might be connected to the first group of trunk contacts, on the selectors, and the second class of connectors to the second group of contacts, and so on. In this manner, line 01, for example, would be selected whenever the following last three digits were called, 101, 201, 301, 401, providing, of course, that any preceding digits called remain the same for all numbers. In each case, however, a different group of connectors would be selected with a result that the corresponding station only on the party line, would be called.

In my improved party line ringing circuit, I connect the different levels or rows of selector contacts referred to in the previous paragraph, to different branches of the same connector, instead of to different classes of connectors. In this way each connector may be made to call any station on a party line, the selection being controlled by the calling line branch over which the connector is operated.

In the accompanying drawings, Figures 1 to

and 2 illustrate my improved ringing circuit. In the first figure a circuit arranged for two stations on a line is shown. In the second figure, a circuit arranged for three or more stations on a line is shown.

5 In these drawings no attempt has been made to show the arrangement of apparatus by means of which a connection is established. My improved ringing circuit is not involved in the establishment of a connection between the calling line and the called line terminals. My improved circuit involves merely the ringing of the called station after the selectors and connector 10 have properly established the physical connection. A complete description of the operation of a selector and party line connector will be found in a patent granted in my name, No. 1,024,184 dated April 23, 1912.

15 In Fig. 1, A represents a station on what we may designate the calling line, and B and C two stations on what we may designate the called line. VL and RL are wires of the calling line connecting the calling 20 station A, through selectors and such other switches (not shown) as may be involved in the connection to the calling branch of the connector at D or at D¹ as the case may be. N represents a line relay 25 controlled by ringing key 3 at the calling station. Line relay N controls the ringing relay P. Calling branch D¹ of the connector includes a relay O, which relay controls the character of ringing power delivered to relay P. VC and RC represent 30 the two wires of the called line, 5 and 7 represent condensers in series with ringers 6 and 8 at stations B and C, respectively. Q and R represent condensers connecting 35 the calling and called branches of the connector.

40 In Fig. 2, A represents the calling station and F, G and H the called stations. Relays N', P', O' and O'' correspond to relays N, P and O, in Fig. 1. J, J¹ and J² represent the different calling branches of the connector, each of which may be selected by the calling station A, depending upon which row or level of the preceding 45 selector is called.

45 The operation of my improved ringing circuit is as follows, reference being made first to Fig. 1 of the accompanying drawings: Station A, as previously stated, can call automatically, either station B or C. To call station B, station A would call such a number as would automatically effect a connection with the connector through branch D. To call station C, station A 50 would call such a number as would automatically effect a connection with the connector through branch D¹. When station A is connected through branch D and ringing key 3 at station A is depressed a circuit 55 is established from earth 2, through 3, 4,

VL, V, winding of N, battery 1 to earth again at 2. The result is that relay N is energized, thereby closing a circuit from earth 2, through 15, 16, winding of P, 1 to 2. Relay P thus energized, causes contact 70 spring 12 to break contact at 13 and make contact at 14 and contact spring 10 to break contact with 9 and make contact with 11. The operation of relay P causes the bell at station B to ring, a circuit being established 75 from earth 2, through ringing generator S, 17, 18, 14, 12, wire VC of calling line through condenser 5, ringer 6 to earth 2. Ringer 8 at station C receives no current from the ringing generator S, and for this 80 reason remains silent. Should station A wish to call station C, connection would be made with the called line through branch D¹. Thus, when the ringing key at station 85 85 is depressed, a circuit is established from A is depressed, a circuit is established from earth 2, through 3, 4, line wire VL to wire V¹ of the branch D¹, through winding of relay O and relay N to battery 1 and earth 2. Both relays O and N are now energized. The energizing of relay N causes relay P 90 to operate as previously described. The result is that ringing generator current is supplied to the calling line in such a manner as to operate the ringer at station C but not at station B, a circuit being established in this case from earth 2, through 95 ringing generator S, 20, 21, 11, 10, condenser 7, ringer 8 to earth 2. The operation of relay O previously referred to, causes contact spring 18 to break contact with 17 and 100 make contact with 19 and swinging spring 21 to break contact with 22 and make contact with 20.

105 It will be noted that when ringing generator current is supplied to one side of the line, the other side of the line is grounded. The object of this is to shunt out the ringer and condenser at the station not being called, so that should the called station answer while ringing current is being supplied to the line, the current passing through the called station's telephone set, now bridged across the line, to the opposite side of the line, will go direct to earth at the central office rather than through the condenser and ringer to earth at the other station on the line.

110 In the circuit just described, reference has been made to the well-known two-party line arrangement in which the ringer at one station is bridged from one side of the line to ground and at the other station from the other side of the line to ground. Where more than two stations on a line are desired, it is now customary to resort to special generators and special ringers, the ringers being so designed as to operate on current from their corresponding generator only. My improved circuit arranged for the use 115 of such ringers and ringing machines is 120 125 130

shown in Fig. 2. The principle involved in the operation of this circuit is the same as in the circuit shown in Fig. 1. Here the calling station A has access to three or more branches on the calling line side of the connector. Three branches are shown in Fig. 2 at J, J¹ and J² respectively. As before stated, the calling station may effect a connection with any branch by calling the proper row or level on the preceding selector. For example, connection with branch J may be effected by calling 4301, and with J¹ by calling 4401 and with J² by calling 4501. To call station F, station A would 15 select calling branch J. To call station G calling station A would select branch J¹. To call station H calling station A would select branch J². The different branches, as before stated being selected automatically 20 when calling the station number. Assume station A to be connected with called line through branch J. When ringing key 3 is depressed a circuit is established from earth 2, through 3, 4, VL, V', winding of 25 N', 1 to 2. Relay N' is now energized and closes a second circuit from earth 2, through 23, 24, winding of P', 1 to 2. Relay P' now operates, causing contact spring 25 to break contact with 26 and make contact with 27, 30 and contact spring 28 to break contact with 30 and make contact with 29. Current is now caused to flow from one pole of ringing generator S¹, through 38, 37, 32, 31, 27, 25, wire VC' of called line, through condensers 43, 45, 47 and ringers 44, 46 and 48 at stations F, G and H respectively, back over wire RC' of called line through 28, 29, 34, 35, 40, 41 to the opposite pole of ringing generator, S¹. As previously stated, the 35 ringers are so designed as to operate on current from their corresponding generator only. Therefore, ringer 44 at station F, which responds to current from generator S¹, operates, the remaining ringers, 46 and 48, remaining silent. To call station G, station A in calling would automatically select the called line through branch J¹. When the ringing key at calling station is depressed, relays O' and N' are energized. 40 Relay N' causes relay P' to operate as previously described. The result is that current flows through the condensers and ringers on the calling line from generator S² causing the operation of ringer 46 which responds to current from generator S². Ringers 44 and 48 remain silent. To call station H, station A in calling would automatically select the called line through branch J². When the 45 ringing key at station A is depressed, relays O'' and N' operate. Relay N' as previously stated, causes the operation of relay P'. The result is that current from generator S² is supplied to the calling line with the result that ringer 48 at station H, which 50 responds to current from generator S² op-

erates, while ringers 44 and 46 remain silent.

In the preceding paragraphs, reference has been made to automatic systems employing a ringing key at the subscribers' stations. By suitable modifications, my improved ringing circuit may be applied to those systems in which a ringing key is not required, that is, to those systems where the ringing of the called subscriber is done 70 automatically, after the desired station number has been called, the bell at the called station, ringing at intervals until the called party answers or until the calling party replaces receiver upon switchhook, in case 75 called party does not answer. In such systems as these, as in the system described in the preceding paragraphs, the relays O, O' and O'' as the case may be, controlling the ringing generator supply, are placed 80 in series with the calling line, substantially 85 as shown and described.

By proper adaptation the principle of selection of the character of the ringing current to be supplied to the called line, depending upon the use of a plurality of calling line branches, may be readily applied to trunking systems in manually operated exchanges. In such systems as these, the operator making the trunking connection to the 90 called station, would have access to as many branches of the trunking circuit as there are classes of stations to be called.

Having thus described my invention, what I claim as new and desire to secure by United 100 States Letters Patent, is:

1. In an automatic telephone system, a connector having party lines terminating thereon, said connector being reached by a plurality of paths, and means for selectively 105 ringing on said party lines, the character of the ringing being controlled by the path over which the connector is reached.

2. In a telephone system, a calling line, a called line, a plurality of stations on said called line, a means of completing connections between said calling and said called lines, said means having one called line branch and a plurality of calling line branches, any of which latter branches may 110 be selected by said calling line, a ringer at each station connected with said called line, arranged to operate only when supplied with a particular kind or arrangement of current, a means of supplying the proper arrangement or kind of current to operate the ringer at any one of said stations connected to said called line, depending upon which of said calling line branches of said means of completing connections between said calling and said called lines, is selected by the calling line.

3. In an automatic telephone system, a calling line, a called line, a plurality of stations on said called line, a connector for 115

- completing connection between said calling and said called lines, said connector having one called line branch and a plurality of calling line branches, any of which latter branches may be selected by said calling line, a ringer at each station connected with said called line, arranged to operate only when supplied with a particular kind or arrangement of current, a means of supplying the proper arrangement or kind of current to operate the ringer at any one of said stations connected to said called line, depending upon which of said calling line branches of said connector is selected by the calling line.
4. In an automatic telephone system, a calling line, a called line, a plurality of stations on said called line, a connector for completing connection between said calling and said called lines, said connector having one called line branch and a plurality of calling line branches, any of which latter branches may be selected by said calling line, a ringer at each station on said called line, arranged to operate only when supplied with a particular kind or arrangement of current, a relay or plurality of relays in series with part or all of said calling line branches of said connector, adapted to supply the proper arrangement or kind of current to operate the ringer at any one of said stations connected to said called line, depending upon which of said calling branches of said connector is selected by the calling line.
5. In an automatic telephone system, a calling line, a called line, two stations on said called line, a connector for completing connection between said calling and said called lines, said connector having one called line branch and two calling line branches, either of which may be selected by said calling line, a ringer at each station of said called line, one bridged from one wire of said called line to earth and the other bridged from the opposite wire of said called line to earth, a relay in series with one of said calling line branches of said connector, adapted to supply current to either side of said called line, depending upon which of the said calling line branches of said connector is selected by said calling line.
6. In a party-line telephone system, a subscriber's line, a connector for seizing said line, means for extending connection to said connector, a plurality of ringing generators, a relay for controlling each of said generators, and means for energizing one of said relays upon the completion of the connection to the connector.
7. In a party-line telephone system, a subscriber's line, a connector for seizing said line, means for extending connection to said connector, a plurality of ringing generators, a relay for controlling each generator, said relays being connected in parallel circuits, and means for energizing one of said relays to control the associated generator upon the completion of the connection to the connector.
8. In a party-line telephone system, a calling and a called subscriber's line, means including a selector and a connector switch for establishing connection between said lines, a plurality of contacts in said selector through which connection may be established with said connector, a plurality of ringing generators, and means for selecting one of said generators to supply ringing current to the called line, the ringing generator selected being dependent upon the contact of the selector switch employed for extending the connection to the connector.
9. In a party-line telephone system a calling and a called subscriber's line, means including a selector and a connector switch for establishing connection between said lines, said selector comprising a bank of contacts arranged in levels, said connector being connected with contacts of a plurality of said levels, a plurality of ringing generators for supplying current to the called line, means for selecting one of said generators, the generator selected being dependent upon the level of the selector employed in extending the connection to the connector.
10. In a party-line telephone system, a calling and a called subscriber's line, a connector for seizing the called line, and means including a selector for extending connection from the calling line to said connector, said selector including a plurality of banks of contacts, multiple connections from a plurality of contacts of one of said banks to said connector, and independent connections from corresponding contacts of a second of said banks to said connector.
11. In a party-line telephone system, a calling and a called subscriber's line, a connector for seizing the called line, and means including a selector for extending connection from the calling line to said connector, said selector including a plurality of banks of contacts, multiple connections from a plurality of contacts of one of said banks to said connector, independent connections from corresponding contacts of a second of said banks to said connector, a plurality of ringing generators for supplying ringing current to the called line, and means controlled over said independent connectors for selecting one of said ringing generators.
12. In a party-line telephone system, a calling and a called subscriber's line, a connector for seizing the called line, and means including a selector for extending connection from the calling line to said connector, said selector including a plurality of banks of contacts arranged in levels, multiple connections between corresponding contacts of a plurality of levels of one or more of said contact banks to said connector, whereby

- connection may be established through a plurality of said levels, independent connections from the corresponding contacts of another of said banks to said connector, a 5 plurality of ringing generators for supplying ringing current to the called line, and means controlled over said independent connections for selecting one of said ringing generators.
- 10 13. In a party-line telephone system, a calling and a called subscriber's line, a connector for seizing the called line, and means including a selector for extending connection from the calling line to said connector,
- 15 said selector including a plurality of banks of contacts, multiple connections from a plurality of contacts of one of said banks to said connector, independent connections from corresponding contacts of a second of 20 said banks to said connector, a plurality of ringing generators in said connector for supplying ringing current to the called line, a relay in each of said independent connections for controlling the selection of one 25 of said generators, and means for energizing one of said relays when connection is made with said connector, the relay energized being dependent upon the level of the selector switch employed in extending 30 the connection.
14. In a party-line telephone system, sub-
- scribers' lines divided into groups, a connector having motion in one plane to select groups and motion in a plane at right-angles thereto to find a line in the selected 35 group for seizing a called subscriber's line, means for extending connection to said connector, a plurality of ringing generators, a relay for controlling each of said generators, and means for energizing one of said relays 40 upon the completion of the connection to the connector.
15. In a party-line telephone system, sub- 45 scribers' lines divided into groups, a connector having motion in one plane to select groups and motion in a plane at right angles thereto to find a line in the selected group for seizing a called subscriber's line, means for extending connection to said connector, a plurality of ringing generators, a 50 relay for controlling each generator, said relays being connected in parallel circuits, and means for energizing one of said relays to control the associated generator upon the completion of the connection to the connector.

Signed by me at San Francisco this 17th day of June, 1911.

GERALD DEAKIN.
